UNITED STATES PATENT OFFICE.

SAMUEL G. SINE, OF PERU, INDIANA, ASSIGNOR OF ONE-HALF TO WM. H. AUGUR, OF SAME PLACE.

COMBINED CRIB AND CRADLE.

SPECIFICATION forming part of Letters Patent No. 293,530, dated February 12, 1884.

Application filed August 6, 1883. (No model.)

To all whom it may concern:

Be it known that I, SAMUEL G. SINE, of Peru, county of Miami and State of Indiana, have invented a new and useful Improvement 5 in Combined Crib and Cradle, of which the following is a specification.

My invention is designed to be used as a child's cradle, and may also be converted into a crib or stationary bed, and relates to that 10 class of cradles which are reciprocated endwise, as in rocking.

In order to aid others skilled in the art to which my invention belongs, I will proceed to describe its construction and operations 15 with reference to the drawing, forming part of this specification, in which—

The figure is an elevated side view of my invention, all of which will be hereinafter fully set forth.

20 The body A of the cradle may be made in any of the usual ways of constructing cradle-bodies, and need not be described. At the head end of the cradle I attach, on opposite sides, a rocker consisting of a hub, F, spindles 25 G, and rocker-foot H. Said parts are pivoted on suitable bearings to give a reciprocating motion endwise to the cradle-body A. I attach to the foot end of the body on opposite sides, below the side rails, a bracket, L. To 30 these brackets I attach pivotally a reciprocating bar, C, being pivoted to the brackets L at c. The upper ends of the reciprocating bars C are pivoted at a to stationary posts or pillars B, said pillars being anchored at the lower 35 ends to a horizontal rail or rails, I. Said rails extend lengthwise of the cradle, and support its weight. The upper outside corner of each rail is rabbeted, forming an inner shoulder or flange, K. In the rabbeted portion of the 40 rails the rocker-feet H have a bearing. The flanges K prevent the head end of the cradle from working laterally, as in rocking the cradle endwise. The rails I are mounted upon casters a' a', so as to move the cradle from 45 room to room.

To convert the cradle into a crib or stationary bed, I provide the hubs F with a lock-pin, O.

Attached to the side rails of the cradle-body are two hasps, M. These hasps are provided with a recess, N.

To lock the parts from reciprocating, the body A of the cradle is moved endwise until the turning of the hubs F brings the pins O in line with the recesses N, formed in the hasps, 55 when said hasp or hasps may be turned down to a horizontal position, when the pin or pins O will pass within the recesses N, thus locking the parts, for the purposes set forth.

As a means for propelling the cradle, I attach to the side, near the center of the body A, the lever E. This lever is provided with a handle at the upper end, and is pivoted to the side of the cradle, and provided with a series of holes near the center to lengthen or shorten 65 the stroke and to increase or decrease the power of propulsion. To the lower end of this lever I pivot a connecting-bar, D, which extends to the reciprocating arm C, to which it is also pivoted.

It is obvious that as the lever E is moved at the upper end toward and from the end of the cradle the body will be caused to reciprocate. It is also obvious that as the cradle is reciprocated the head end is caused to move 75 to and fro in a true line or on a level, while the foot end, by the swinging of the arms C, is caused to slightly rise and fall in its movements.

Having thus described my invention as fully 80 as I can, what I claim as new, and desire to secure by Letters Patent, is—

1. The combination of a crib, stationary supports therefor, and links connecting the crib at one end with such supports, and rockers, 85 substantially as described, pivoted to the crib at its opposite end, as and for the purposes specified.

2. The combination of a base, stationary supports attached thereto, a crib, rockers, 90 substantially as described, pivoted to the crib at one end and mounted on said base, and links connecting the opposite end of the crib to the stationary supports, as and for the purposes set forth.

SAMUEL G. SINE.
